US00D868896S

(12) **United States Design Patent** (10) **Patent No.:** **US D868,896 S**
(45) **Date of Patent:** **** Dec. 3, 2019**

(54) **DIGITAL SIGN**

- (71) Applicant: **LG ELECTRONICS INC.**, Seoul (KR)
- (72) Inventors: **Yoonkyeong Lee**, Seoul (KR); **Sangwon Yoon**, Seoul (KR); **Yongho Lee**, Seoul (KR); **Hyeyoung Hong**, Seoul (KR)
- (73) Assignee: **LG Electronics Inc.**, Seoul (KR)
- (**) Term: **15 Years**
- (21) Appl. No.: **35/505,263**
- (22) Filed: **Jan. 4, 2018**

(80) **Hague Agreement Data**

Int. Filing Date: **Jan. 4, 2018**
Int. Reg. No.: **DM/099227**
Int. Reg. Date: **Jan. 4, 2018**
Int. Reg. Pub. Date: **Jul. 13, 2018**

(30) **Foreign Application Priority Data**

- Jul. 5, 2017 (KR) 30-2017-0030883
- (51) LOC (12) Cl. 20-03
- (52) U.S. Cl. USPC D20/10
- (58) **Field of Classification Search**
USPC D20/10, 18, 19, 21, 41, 42, 99; D14/127, D14/373
CPC ... G09F 7/00; G09F 7/02; G09F 13/04; G09F 19/02

See application file for complete search history.
